HOD STAND

Harry M. Young, Jr., Webster Groves, Mo.

Application March 17, 1947, Serial No. 735,208

3 Claims. (Cl. 248—166)

1

This invention relates generally to hod stands and, more particularly, to portable hod stands.

It is the primary object of the present invention to provide a hod stand which is durable and rugged in construction and operation.

It is an additional object of the present invention to provide a hod stand which can be quickly folded up into a compact readily portable unit and can be conveniently set up again wherever needed.

It is a further object of the present invention to provide a hod stand capable of accommodating hods of various lengths and sizes.

With the above and other objects in view, my invention resides in the novel features of form, construction, arrangement, and combination of parts presently described and pointed out in the claims.

In the accompanying drawings (two sheets), Figure 1 is a front elevational view of a hod stand constructed in accordance with and embodying my present invention;

Figure 2 is a fragmentary rear view of the hod stand;

Figure 3 is a fragmentary front perspective view of the hod stand;

Figure 4 is a top plan view of the hod stand;

Figure 5 is a transverse sectional view taken along line 5—5 of Figure 1;

Figure 6 is a front elevational view of a modified form of hod plate constructed in accordance with and embodying the present invention;

Figure 7 is a front elevational view of the supplemental plate forming part of the present invention; and

Figure 8 is a fragmentary sectional view taken along line 8—8 of Figure 6.

Referring now in more detail and by reference characters to the drawings, which illustrate practical embodiments of the present invention, A designates a tripodod hod stand comprising a rectangular plate 1, fabricated preferably of heavy gauge sheet metal, supported by legs 2, 3, 4, of tubular metallic construction. Legs 2, 4, are uniform in length and are pivotally mounted at their upper ends to the rear face of the plate 1 by bolts 5, 6, respectively, for swinging movement parallel to the plane of the plate 1. When being swung outwardly into supporting disposition, the legs 2, 4, are arrested by curved retaining clips 7, 7', respectively, welded or otherwise suitably fixed on the rear face of the plate 1. The leg 3, of greater length than the legs 2, 4, is pivoted between ears 8, 8', similarly welded on the central portion of the rear face of plate

2

1 for swinging movement in a plane perpendicular to the plane of the plate 1. The upper end 9 of the leg 3 is provided with an inwardly and downwardly sloping face 10 to abut against the rear face of plate 1 when the leg 3 is moved outwardly into supporting disposition. Respective inward movements of the legs 2, 3, 4, bring them together, as shown in dotted lines in Figure 1, for convenient portability.

15 The legs 2, 3, 4, are provided at their lower ends with cast foot sections 11 having outwardly extending flanges 12 at their base. Said sections 11 are diametrically decreased at their upper ends for fitting within the lower sections of the legs 2, 3, 4, and are retained therein by a rivet 13 extending through apertures 14, 14', in the legs 2, 3, 4, and aligned aperture 15 of the sections 11.

20 The forward face of the plate 1 is provided with angle members 16, 16', swivelly mounted on the forward ends of the bolts 5, 6, respectively, which extend through the apertures 17, 17', of the plate 1. Firm tightening of the bolts 5, 6, sets the angle members 16, 16', rigidly at the desired angle, depending upon the size and shape of the hod which is to be rested against the stand A for appropriate loading.

25 In use, the hod stand A is set up by the hod carrier in close and convenient proximity to the pile of bricks or mortar from which he is loading his hod. The hod b (shown schematically by dotted lines in Figure 5) is set in the stand with the trough portion resting in the angle members 16, 16', and the hod handle extending downwardly to the ground midway between the stand legs 2, 4. The hod b may then be loaded conveniently and, when loaded, may be quickly and simply transferred by the hod carrier to his shoulder. It should be noted that the hod b is quite securely supported by the hod stand A and yet the hod b can be removed from the stand A with a minimum of effort.

30 In some localities, it is a safety requirement that the hod be supported by a hod stand from which it cannot fall accidentally and some convenience and speed of handling must, if necessary, be sacrificed to this end. For such purpose, a modified form of hod stand A' may be provided as shown in Figures 6, 7, and 8. The modified form of hod stand A' is substantially identical with the previously described stand A, including a plate 1, collapsible legs 2, 3, 4, bolts 5, 6, and angle members 16, 16'. The hod stand A' is, however, provided with a supplemental plate 18 mounted slidably upon the forward face

of the plate 1 and held in place underneath the angle members 16, 16', by the bolts 5, 6, extending through elongated parallel slots 19, 19'. Along its upper margin, the plate 1 is provided with a V-shaped recess 20 adapted to receive and hold the hod when the plate 18 is in upward position, as shown in Figure 6, and the pole or handle of the hod extends loosely between the angle members 16, 16'. In such position, the hod cannot accidentally fall down, spilling its contents, although when so supported the loaded hod must be lifted bodily upwardly and out of the recess 20, a somewhat more laborious and time-consuming operation than that resulting when the angle members 16, 16', are used. It should be noted that the slots 19, 19', are of such length that the plate 18 can be dropped to a relative position in which the upper margins of the plates 1 and 18 coincide, in which case the hod stand A' may be used in precisely the same manner as the previously described hod stand A.

It should be understood that changes and modifications in the form, construction, arrangement, and combination of the several parts of the hod stand may be made and substituted for those herein shown and described without departing from the nature and principle of my invention.

Having thus described my invention, what I claim and desire to secure by Letters Patent is:

1. A hod stand comprising a metallic rectangular plate, two bolts extending through said plate, two laterally swingable leg members respectively mounted at their upper ends on said bolts, angle clips mounted on the other end of said bolts, a central leg member longer than said laterally swingable leg members swingably mounted in the central portion of the rear face of said plate, and an auxiliary plate slidably mounted between the angle clips and the rectangular plate and being provided along its upper edge with a notch for holding a hod trough.

2. A hod stand comprising a rectangular plate,

10
5

a supplemental plate provided with a V-shaped indentation, bolts extending through apertures in said rectangular plate and aligned longitudinal apertures in the supplemental plate, angle clips mounted on one end of said bolts, lateral uniform leg members swivelly mounted at their upper ends on the other end of said bolts, curved retaining plates mounted on the rear face of said rectangular plate, a central leg member longer than said lateral leg members swingably mounted on the rear face of said rectangular plate, and cast foot members provided on the lower ends of said leg members.

15
25
30
35
40

3. A hod stand comprising a rectangular plate, an auxiliary plate provided with spaced aligned longitudinal apertures, bolts extending through apertures in said rectangular plate and said longitudinal apertures in the auxiliary plate whereby said auxiliary plate may be shiftably moved in relation to the rectangular plate, angle clips mounted on the extended ends of said bolts, said auxiliary plate being furthermore provided with a V-shaped indentation in its upper margin for removably supporting hods, and rearwardly swingable leg means provided on the rear face of the rectangular plate.
